UNITED STATES PATENT OFFICE.

OTTO PERGL, OF CLEVELAND, OHIO.

DESIGN FOR A WIRE-ENTANGLEMENT CUTTER.

53,104.

Specification for Design.

Patented Mar. 18, 1919.

Application filed December 17, 1917. Serial No. 208,086. Term of patent 3½ years.

To all whom it may concern:

Be it known that I, OTTO PERGL, a subject of the Emperor of Austria, residing in the city of Cleveland, in the county of Cuyahoga and State of Ohio, have invented a new, original, and ornamental Design for a Wire-Entanglement Cutter, of which the following is a specification, reference being had to the accompanying drawing, forming part thereof.

Figure 1 illustrates a view in side elevation of my new ornamental entanglement cutter and Fig. 2, a plan view thereof.

I claim:

The ornamental design for a wire entanglement cutter, as shown.

In witness whereof, I have hereunto subscribed my name this 11 day of December, 1917.

OTTO PERGL.
